In the Netherlands November 27, 1941

Section 1, Public Law 690, August 8, 1946
Patent expires November 27, 1961

17 Claims. (Cl. 315—5)

1

This invention relates to a discharge tube adapted for generating oscillations of preferably ultra-high frequency, in which an electron beam is produced and led successively along a velocity control electrode system constituted by at least three electrodes, a drift-space electrode and a second electrode system also constituted by at least three electrodes.

The present invention has for its purpose to provide a form of construction of such a discharge tube, in which a symmetrical arrangement of the electrode systems is ensured.

According to the invention, this object is attained by that the remote outer electrodes of the electrode systems are each connected, to the wall of a cylindrical drum, whose axis is parallel to the axis of the discharge tube, said drums constituting the outer conductors of those parts of the feedback line which are contiguous to the electrode systems, while these drums are supported by the wall of the tube or at least the circular surfaces thereof constitute a part of the wall of the tube.

The invention will be more clearly understood by reference to the accompanying drawings, in which

Fig. 1 shows one constructional example of a device according to the invention in longitudinal section.

Figs. 2a and 2b are cross-sectional views taken on the line II—II of the device shown in Fig. 1, Fig. 2b being an alternate embodiment of the structure shown in Fig. 2a, and

Figs. 3, 4 and 5 show other constructional examples of the device according to the invention.

The device shown in Fig. 1 comprises an envelope 1 of glass or quartz, containing an electrode system for producing an electron beam which is constituted by an indirectly heated cathode 2, a grid 3 and an accelerating electrode 4, the last-mentioned electrode having applied to it a voltage which is positive relatively to the cathode 2. At the end which is remote from the said electrode system, the envelope 1 contains a collector electrode 6 and an electrode 7 which serves to catch the primary electrons which may be reflected by the electrode 6 and the emitted secondary electrons.

On their way from the cathode to the collector electrode 6, the electrons emitted by the cathode 2 are led along at least two electrode systems,

2

of which the first, the velocity control electrode system, is constituted by three electrodes, namely, control electrode 8 and two bounding electrodes 9 and 10. The bounding electrode 10 is constituted by an extremity of the drift-space electrode 11 which constitutes a so-called drift-space through which the electron beam is led after having passed the control-electrode system. Subsequently, the electron beam is led along the second electrode system which is also constituted by three electrodes, namely, electrode 12 and two bounding electrodes 13 and 14, of which the latter is constituted by that extremity of the drift-space electrode 11 which is remote from the velocity control electrode system.

For generating oscillations, the second electrode system 12, 13, 14 is connected to the velocity control electrode system through the intermediary of a feedback line.

20 The operation of the described discharge tube as a device for generating oscillations will not be described, since it may be assumed as known. The invention relates to the constructional arrangement of the discharge tube and more particularly of the feedback line which connects the electrode systems 8, 9, 10 and 12, 13, 14 and, together with these electrode systems, constitutes the oscillatory system, which determines the frequency of the oscillations to be generated.

According to the invention, the outer conductor of that part of the feedback line which is connected to the electrode systems 8, 9, 10 and 12, 13, 14 is constituted by two cylindrical drums, of which the axes coincide with, or are at least parallel to the axis of the discharge tube and of which the remote walls 15 and 16 are connected respectively to the remote outer electrodes 9 and 13 of the two electrode systems. The adjacent walls 17 and 18 in the present form of construction are connected to the adjacent outer electrodes 10 and 14 of the electrode systems. The circular surfaces of the drums are designated 19 and 20 respectively. The two drums are connected by means of a cylindrical conductor 21 which constitutes the outer conductor of the remaining part, preferably co-axial, of the feed-back line. The inner conductor of the feed-back line, which extends between the circular surfaces 19 and 20 of the two drums and connects the inner electrodes 8 and 12, is designated 22 and may also be constituted by a tubular conductor.

The drums 15, 17, 19 and 16, 18, 20 are supported by the tube wall by means of local re-entrant parts 23 which are engaged by mica supporting discs 24 and 25 which are forced against the walls 15 and 16 of the drums by means of discs 26 and 27 respectively. The shape of the mica discs is such that the whole oscillatory system, which is constituted by the two electrode systems 8, 9, 10 and 12, 13, 14 and the feedback line, may be shoved into the envelope 1, beyond the re-entrant parts 23, into the correct position, whereafter by means of a slight rotation of the whole system the mica discs may be caused to engage the re-entrant parts 23, thus supporting the whole back-coupled system.

A supply-conductor 28 is connected to the circular surface 19 of the drum 15, 17, 19 for the purpose of applying to the electrodes 8 to 14 a high positive voltage relatively to the cathode.

Figs. 2a and 2b, which are cross-sectional views taken on the line 2a—2a of the discharge tube represented in Fig. 1, show in what manner the energy of the oscillatory system which is constituted by the electrodes 10 to 14 and the feedback line may be abstracted. The energy is abstracted from the central electrode 12 of the second electrode system by means of a conductor 29 which is movably arranged in a re-entrant part of the tube wall which is of non-conductive material and capacitatively coupled to the electrode 12. The wall 30 of the reentrant part is made, preferably at least in part, of glass or quartz. Further, the energy abstracting conductor 29, which may also serve as an aerial for emitting the generated oscillations, is preferably normal to the circular surface 20 of the cylindrical drum 15, 18, 20.

It is also possible for the energy abstracting conductor 29 to be arranged within the tube wall, in which case the tube wall has to be provided with a protuberance of glass or quartz 30', which is indicated at 29' in Fig. 2a. In this case magnetic means may be used for the adjustment of the conductor 29', which is slidably supported within protuberance 30' by means of spacers 29''.

When the conductor 29 (or 29') is displaced, the capacitative coupling of the conductor 29 with the electrode 12 varies and this results in the energy abstracted from the oscillatory system being also varied. Further, it has been found that it also depends on the spacing between the conductor 29 and the electrode 12, which of the different frequencies which are determined by the dimensions of the oscillatory system constituted by the electrode systems 8, 9, 10 and 12, 13, 14 and the feedback line, will occur so that a variation of the spacing may bring about a discontinuous variation in frequency.

In the form of construction shown in Figs. 1 and 2, the back-coupled system is completely surrounded by a glass envelope. However, as is shown in the forms of construction of Figs. 3 and 4, it is also possible to shape the electrode 13 into the form of a hollow conductor closed at the end which is remote from the drift-space electrode 11, which conductor constitutes the wall of the tube and of which that extremity which is remote from the wall 16 serves as a collector electrode.

Fig. 3 shows a simplified form of construction of the discharge tube according to the invention represented in Figs. 1 and 2. The simplification consists in the construction of that part of the feed-back line which connects the two drums 15, 17, 19 and 16, 18, 20. In this form of construction, the outer conductor of the said part of

the feedback line is constituted by the inner surface of a bore in a solid, conductive, cylindrical body 31 which has the same diameter as the drums and is arranged co-axially thereof.

In this case the drift-space electrode 11 is constituted by the inner surface of a second bore in the said body 31, while the end surfaces of the body 31 constitute the adjacent walls, connected to the electrodes 10 and 14, of the cylindrical drums of which the walls 15 and 16 are connected respectively to the remote outer electrodes 9 and 13. Another feature of the form of construction shown in Fig. 3 consists in that the circular surfaces 19 and 20 of the cylindrical drums and of the body 31 form a part of the tube wall, while the remote outer electrodes 9 and 13 of the electrode systems 8, 9, 10 and 12, 13, 14 have sealed to them parts of the tube wall which are made of glass or quartz. Further, in this form of construction, the oscillations generated in the oscillatory system constituted by the electrode systems 8, 9, 10 and 12, 13, 14 and the feedback line are derived from this system by abstracting energy from the electronic beam by means of a resonator, for example a cavity resonator 32 which is constituted by a cylindrical drum whose axis coincides with, or is at least parallel to the axis of the discharge tube. In this drum the opposite walls 33 and 34 are provided with apertures which are opposite to each other in the direction of the electron beam and are passed by the latter. The electron beam, whose intensity varies in the rhythm of the generated oscillations, generates oscillations in the resonator 32 on passing the latter, of which oscillations the frequency is either equal to, or a harmonic of the frequency of the oscillations generated by the said oscillatory system. For adjusting the natural frequency of the resonator, the spacing between the wall 33 and the screw 36, and hence the capacity of the resonator may be varied by means of a screw 36.

The oscillations generated in the resonator may be supplied to a load circuit by means of a coupling loop 35 or in any other manner.

In order to avoid excessive heating of that part of the tube wall which is located inside the cavity resonator, use may be made of air-cooling for this part of the tube wall. The cooling air may be blown through an aperture into the resonator and passes out along the gaps which exist between the tube wall to be cooled and the resonator, as is shown by arrows in the figure.

Excessive heating at the place of the collector electrode 6 is preferably avoided by utilizing a water-cooled collector electrode. The cooling jacket is designated 37 and is traversed by cooling liquid in the direction indicated by arrows.

The discharge tube shown in Fig. 4 corresponds substantially to that shown in Fig. 3.

The difference only consists in that the resonator 32' and the collector electrode 6 form a part of the tube wall and the distance between the middle of the wall 33' of the resonator and that of the wall 34', which is made flexible, is adjustable. The adjustment is effected by means of screws 38. On displacing these screws a wall 39 secured to the collector electrode 6 is displaced and, in addition to the wall 39, the collector electrode 6' and the middle of the flexible wall 34' of the resonator. Furthermore, the discharge tube shown in Fig. 4 comprises energy abstracting conductor 40 which may serve, in addition, as an aerial and is inductively coupled to the resonator 32'.

In the form of construction shown in Fig. 5,

the outer conductor 21' of the feedback line is solely constituted by the cylindrical drums 15', 17', 21' and 16, 18', 21' which for this purpose have a side wall 17', 18' in common. This side wall, which corresponds to the side walls 17 and 18 of the drums in the other figures, is connected to the middle of the drift-space electrode 11. For the purpose of obtaining a symmetrical arrangement, the remote outer electrodes 9' and 13' in this form of construction have a length which is approximately equal to half the length of the drift-space electrode 11.

Furthermore, as already mentioned before, the electrode 13' is shaped into the form of a cylinder closed at the end which is remote from the drift-space electrode 11, which cylinder constitutes a part of the tube wall and of which that end which is remote from the wall 16 serves as a collector electrode.

We claim:

1. An electron discharge tube comprising in the order indicated means to generate an electron beam, a first cavity resonator, a velocity-control electrode assembly in said first cavity resonator, a second cavity resonator, a second electrode assembly in said second cavity resonator, a drift electrode member coupling said assemblies together, said velocity-control and second electrode assemblies each comprising a bounding electrode, an end portion of said drift electrode member and a central electrode interposed between said bounding electrode and the respective end portion of said drift electrode member, said assemblies and said member being adjacent the path of said electron beam, and a transmission line coupling said velocity-control electrode assembly to said second electrode assembly, said transmission line comprising an outer tubular conductor and an inner conductor within said outer tubular conductor, said inner conductor being coupled at each end to the central electrode of the respective electrode assembly, said first and said second cavity resonators comprising cylindrical drums having axes parallel to the axis of said drift electrode member and constituting the outer conductor of those portions of said transmission line contiguous to said drums.

2. An electron discharge tube as claimed in claim 1 wherein said cavity resonators have wall portions in common and the outer conductor of said transmission line is constituted by the cylindrical surface of an aperture in said common wall portions through which the inner conductor of said transmission line passes.

3. An electron discharge tube as claimed in claim 1 comprising a solid, cylindrical, conducting member having an outer diameter equal to the outer diameter of said drum and being coaxially interposed between said drums, and the outer conductor of said transmission line is constituted by the cylindrical surface of a bore in said solid member connecting said cavity resonators.

4. An electron discharge tube as claimed in claim 1 comprising a solid, cylindrical, conducting member having an outer diameter equal to the outer diameter of said drum and being coaxially interposed between said drums, the outer conductor of said transmission line being constituted by the cylindrical surface of a first bore in said solid member connecting said cavity resonators, and said drift electrode member being constituted by a second bore in said solid member connecting said cavity resonators.

5. An electron discharge tube for generating

oscillations comprising, an envelope, means to generate an electron beam, a first cavity resonator, a velocity-control electrode assembly in said first cavity resonator, a second cavity resonator, a second electrode assembly in said second cavity resonator, a drift electrode member interposed between and coupling said velocity-control electrode and said second electrode assemblies, a third cavity resonator, a third electrode assembly in said third cavity resonator, said velocity-control and second electrode assemblies each comprising a bounding electrode, an end portion of said drift electrode member and a central electrode interposed between said bounding electrode and the respective end portion of said drift electrode member, said third electrode assembly comprising two bounding electrodes in opposing walls of said third cavity resonator, a transmission line coupling said velocity-control electrode assembly to said second electrode assembly, said transmission line comprising a tubular conductor and another conductor within said tubular conductor, said first and second cavity resonators comprising a portion of said envelope, said first, said second and said third cavity resonators being adjacent the path of said electron beam, and output electrode means in said third cavity resonator.

6. An electron discharge tube comprising in the order indicated means to generate an electron beam, a first cavity resonator, a second cavity resonator and a third cavity resonator adjacent the path of said electron beam, a velocity-control electrode assembly in said first cavity resonator, a second electrode assembly in said second cavity resonator, a drift electrode member coupling said assemblies together, said velocity-control and second electrode assemblies each comprising a bounding electrode, an end portion of said drift electrode member and a central electrode interposed between said bounding electrode and the respective end portion of said drift electrode member, and a transmission line coupling said velocity-control electrode assembly to said second electrode assembly, said transmission line comprising an outer tubular conductor and an inner conductor within said outer tubular conductor, said inner conductor being coupled at each end to the central electrode of the respective electrode assembly, said first and said second cavity resonators comprising cylindrical drums having axes parallel to the axis of said drift electrode member and constituting the outer conductor of those portions of said transmission line contiguous to said drums, said third cavity resonator having apertures in opposing walls through which path of said electron beam passes.

7. An electron discharge tube as claimed in claim 6 wherein said third cavity resonator comprises a cylindrical drum having an axis parallel to the axis of said drift electrode member and having an end portion adjustable in the direction of said axis.

8. An electron discharge tube for generating oscillations comprising, in the order indicated a heater, a cathode, a grid, an accelerating electrode, a first cavity resonator, a velocity-control electrode assembly in said first cavity resonator, a second cavity resonator, a second electrode assembly in said second cavity resonator, a drift electrode member interposed between and coupling said velocity-control electrode and said second electrode assemblies together, said velocity-control and second electrode assemblies each

comprising a bounding electrode, an end portion of said drift electrode member and a central electrode interposed between said bounding electrode and the respective end portion of said drift electrode member, said first and said second cavity resonators being constituted by a hollow cylindrical member having two end walls having central apertures in which the bounding electrodes are positioned and a central wall having a first aperture in which said drift electrode member is positioned and a second aperture through which a tubular conductor passes, said tubular conductor connecting the central electrodes of said electrode assemblies to couple said cavity resonators, said assemblies and said member being adjacent the path of said electron beam, and the bounding electrode of said second electrode assembly constituting the collector electrode.

9. An electron discharge tube for generating oscillations comprising, an envelope and within said envelope, a heater, a cathode, a grid, an accelerating electrode, a further electrode, a collector electrode, a first cavity resonator, a velocity-control electrode assembly in said first cavity resonator, a second cavity resonator, a second electrode assembly in said second cavity resonator, a drift electrode member interposed between and coupling said velocity-control electrode and said second electrode assemblies together, the axis of said drift electrode member coinciding with the axis determined by said cathode and said collector electrode, said velocity-control and second electrode assemblies each comprising a bounding electrode, an end portion of said drift electrode member and a central electrode interposed between said bounding electrode and the respective end portion of said drift electrode member, said cavity resonators being mounted within said envelope and being interposed between said accelerating electrode and said further electrode, a transmission line coupling said velocity-control electrode assembly to said second electrode assembly, said transmission line comprising a tubular conductor and another conductor within said tubular conductor, said inner conductor being coupled at each end to the central electrode of the respective electrode assemblies, said first and said second cavity resonators comprising cylindrical drums having axes parallel to the axis of said drift electrode member, the outer conductor of said transmission line terminating in said drums.

10. An electron discharge tube as claimed in claim 9 in which said envelope is provided with a re-entrant portion adjacent the central electrode of one of said electrode assemblies.

11. An electron discharge tube as claimed in claim 9 in which said envelope is provided with a protuberance adjacent the central electrode of one of said electrode assemblies and comprising an adjustable conductor capacitively coupled to said central electrode and mounted in said protuberance.

12. Apparatus comprising an electron discharge tube as claimed in claim 29 in which said envelope is provided with a re-entrant portion adjacent the central electrode of one of said electrode assemblies and having an adjustable conductor capacitively coupled to said central electrode and positioned in said re-entrant portion.

13. An electron discharge tube for generating oscillations comprising, an envelope, means to generate an electron beam, a first cavity resonator, a velocity-control electrode assembly in

said first cavity resonator, a second cavity resonator, a second electrode assembly in said second cavity resonator, a drift electrode member interposed between and coupling said velocity-control electrode and said second electrode assemblies together, a third cavity resonator, a third electrode assembly arranged in said third cavity resonator, said velocity-control and second electrode assemblies each comprising a bounding electrode, an end portion of said drift electrode member and a central electrode interposed between said bounding electrode and the respective end portion of said drift electrode member, a transmission line coupling said velocity-control electrode assembly to said second electrode assembly, said transmission line comprising a tubular conductor and another conductor within said tubular conductor, said first and second cavity resonators being constituted by a cylindrical, solid, conducting member having cavities at each end connected by a central bore constituting said drift electrode member and a second bore constituting said outer tubular conductor of said transmission line through which said inner conductor passes, the outer portion of said solid member forming a portion of said envelope, said third electrode assembly comprising two bounding electrodes in opposing walls of said third cavity resonator, said first, said second and said third cavity resonators being adjacent the path of said electron beam, and output electrode means arranged in said third cavity resonator.

14. An electron discharge tube as claimed in claim 13 wherein that portion of said envelope beyond said first and second cavity resonators is composed of insulating material and said third cavity resonator surrounds said envelope.

15. An electron discharge tube as claimed in claim 13 wherein said third cavity resonator is provided with an adjustable member constituting one of said bounding electrodes and forming tuning means for said third cavity resonator.

16. An electron discharge tube for generating oscillations comprising, an envelope and within said envelope, a heater, a cathode, a grid, an accelerating electrode, a further electrode and a collector electrode, a first cavity resonator, a velocity control electrode assembly in said first cavity resonator, a second cavity resonator, a second electrode assembly in said second cavity resonator, a drift electrode member interposed between and coupling said velocity-control electrode and said second electrode assemblies together, the axis of said drift electrode member coinciding with the axis determined by said cathode and said collector electrode, said velocity-control and second electrode assemblies each comprising a bounding electrode, an end portion of said drift electrode member and a central electrode interposed between said bounding electrode and the respective end portion of said drift electrode member, said cavity resonators constituting a portion of said envelope and being interposed between said accelerating electrode and said further electrode, a transmission line coupling said velocity-control electrode assembly to said second electrode assembly, said transmission line comprising a tubular conductor and another conductor within said tubular conductor, said inner conductor being coupled at each end to the central electrode of the respective electrode assemblies, said first and said second cavity resonators comprising cylindrical drums having axes parallel to the axis of said

drift electrode member, the outer conductor of said transmission line terminating in said drums.

17. An electron discharge tube as claimed in claim 16 comprising a protuberance on one of said drums adjacent one of the central electrodes of one of said electrode assemblies and an adjustable conducting electrode capacitively coupled to said central electrode and within said protuberance.
